UNITED STATES PATENT OFFICE.

LAZARUS ROSENTHAL, OF PITTSBURGH, PENNSYLVANIA.

EXTERNAL ARCH SUPPORT FOR SHOES.

Application filed July 29, 1924. Serial No. 722,879.

To all whom it may concern:

Be it known that I, LAZARUS ROSENTHAL, a citizen of the United States, residing at Pittsburgh, in the county of Allegheny and State of Pennsylvania, have invented certain new and useful Improvements in External Arch Supports for Shoes, of which the following is a specification.

This invention is for arch supports of the type applied to the bottom of a shoe, as distinguished from those used inside the shoe.

It is well recognized by those who have made a study of the foot, that when one is standing, or walking, the weight of the body is thrown entirely on the arches of the feet. When one is walking, particularly, the entire weight of the body is alternately shifted from one foot to the other. Each arch, therefore, is subject to the impact of one's weight several times a minute. As this weight in the average adult is considerable, it will be readily seen that during the day, each arch is subject to a tremendous strain. This results in the stretching and straining 25 of the muscles and ligaments of the feet and legs and in the dislocation of the bones of the arch, producing a tired feeling in the legs, pains in the legs, and even the lower part of the back, and excruciating pains in 30 the feet, and leads to the development of bunions and calli.

Considerable relief can be obtained by the use of arch supports of various kinds inside the shoe, but, if the arch of the shoe itself is not sufficiently rigid or is improperly shaped, internal supports do not give proper relief. While various devices have been provided along the general line of the present invention for application to the under side 40 of the arch of the shoe, the present invention has for its object to provide an improved external support designed to produce an active counteracting pressure to the downward strain on the arch of the foot at its point of greatest strain and weakness and, at the same 45 time, support the entire arch of the foot.

The invention has for its further object to provide such a support which will be shaped to assist the wearer in acquiring a 50 more comfortable manner of walking.

The invention may be readily understood by reference to the accompanying drawing, in which:

Fig. 1 is a side view of the bottom of a shoe having my invention applied thereto, the skeleton of the foot being indicated in

dotted lines, the view showing the inside of the shoe;

Fig. 2 is a bottom plan view of Fig. 1;

Fig. 3 is a view corresponding to Fig. 1, 60 showing only a part of the shoe and being on a larger scale;

Fig. 4 is a transverse section through the arch support in the plane of line IV—IV of Fig. 3;

Fig. 5 is a view similar to Fig. 3, showing a slightly modified construction;

Fig. 6 represents a longitudinal section through a further modified form.

The invention may be best understood by 70 explanation of its function and location with respect to the bones of the foot, and for this reason, the skeleton of the foot has been shown in dotted lines in Figs. 1 and 2. In these views, the skeleton is approximately in 75 the position that it assumes in the shoe.

In the drawings, 5 designates the upper of a shoe having a heel 6 and a sole 7, upwardly arched in the usual manner at 8. The shank of the shoe falls directly below the 80 arch of the foot.

The arch of the foot includes the heavy heel bone *a*, known as the os calcis. Setting on this bone is the astragalus *b* which forms the keystone of the arch, and which articulates with the heavy bone of the lower leg, so that the load of the body is thrown directly on this bone. A forward extension *a'* of the os calcis bears against the cuboid bone *c*, forming the lower or outer side of the 90 arch. An extension *b'* of the astragalus bears against scaphoid bone *d*, the scaphoid having a lateral face which bears against the cuboid bone *c* at *d'*.

At the point of juncture of the astragalus, 95 the scaphoid and the cuboid bones, which point is designated *F*, is the weak point of the arch and the one where the greatest weight is placed. Articulating with the scaphoid bones are the final bones of the arch, the internal, middle and external cuneiform bones, designated *g*, *g'*, and *g''* respectively. Articulating with the cuneiform and cuboid bones are the five metatarsal bones *h*, the joint *h'* being the metatarsal joint.

According to the present invention, there is secured to the bottom of the shoe, against the heel of the shoe, a resiliently compressible block 10, which may be of rubber. The block is of substantially the same thickness 110 as the heel throughout the rear portion of its length, but has a forwardly extending

tapered portion 11. The overall length of the block is less than the length of the shank of the shoe, so that the forward end of the block terminates at a point just below the 5 metatarsal joint. The non-tapering portion of the block is substantially entirely back of all the cuneiform bones.

On the lower face of the non-tapering portion of the block is a slight projection 12 10 that falls directly below the point F. This projection covers a relatively small area of the block, but is sufficiently large to fall under the point F within a certain range of sizes for shoes, so that one size of support may fit several sizes of shoes efficiently.

It will be seen that when the foot is lowered to the ground, the load will first come on the projection, and actually create an upward pressure on the under side of 20 the arch, particularly to point F and the zone immediately surrounding it, it being understood that, in accordance with known physical principles, the lines of force upwardly will spread out in cone fashion away 25 from the projection. In this manner, an effective counter pressure is put on the arch, serving to relieve it of its load. The main body of the block will assist in resiliently holding the arch of the shoe firm and giving 30 support to the less heavily strained parts of the foot.

By reason of the tapered forward end of the support, little upward pressure or added 35 rigidity is obtained under the forward part of the arch and the metatarsal joints, whereby by the shoe and the bones of the foot may more naturally adjust themselves, and the joints move more freely. At the same time, added support is given to the cuneiform 40 bones.

By making the non-tapering part of the block slightly thicker or higher on the inner side than on the outer, as shown in Fig. 4, less upward pressure or support will be 45 given the outer side of the foot, tending to throw the weight to the outer side of the foot. Walking with the weight thrown to the outer and the stronger side of the arch is a corrective for strained or fallen arches, 50 and it is the proper way to walk to avoid such trouble.

In Fig. 5, I have shown the non-tapering portion of the block as having a slight convexity at the desired point back of the 55 tapered part, to give substantially the same effect as the projection 12. In this figure, 13 is the non-tapered portion, 14 the tapered

portion, and 15 the convex portion that extends below the heel.

In Fig. 6, the construction is generally 60 similar to that shown in Fig. 4, but a metal button 16 is molded into the block. This serves the same purpose but wears less rapidly than the integral rubber projection 12 of Fig. 4. 65

The device may be retained in position in the same manner that rubber heels are generally secured, that is, by nails and metal bushings, as indicated in Fig. 3, although any suitable fastening means may be used. 70

The invention may be used advantageously, in severe cases of broken arches, with an internal support of the kind shown in my co-pending application Serial No. 694,157, filed February 20, 1924. 75

I claim as my invention:

1. An arch support adapted to be secured to the shank of a shoe comprising a resiliently compressible elongated body having a rear portion of substantially constant 80 thickness throughout its length, a tapering forward portion, and a button of less length and width than the body projecting from the lower face of said rear portion thereof.

2. An arch support adapted to be secured 85 to the shank of a shoe comprising a resiliently compressible elongated body having a rear portion of substantially constant thickness throughout its length, a tapering forward portion, and a metal button of less 90 length and width than the body molded into the body and projecting from the lower face of said rear portion thereof.

3. The combination with a shoe having a heel and a sole, said sole being arched in 95 the usual manner, of an arch support comprising a block secured to the under surface of the shank having a rear portion of substantially the same thickness as the heel throughout its length, and a front portion 100 of forwardly decreasing thickness, said rear portion having a projection on the lower face thereof extending below the plane of the bottom of the heel, said projection being so positioned with respect to the shank of 105 the shoe as to be substantially under the juncture of the astragalus, scaphoid and cuboid bones of the foot of a wearer to which the shoe is fitted, said rear portion of the body being thickest on the inner side of 110 the shoe.

In testimony whereof, I affix my signature.

LAZARUS ROSENTHAL.
